Primary Examiner — Austin Murphy(74) *Attorney, Agent, or Firm* — Arch & Lake LLP(57) **CLAIM**

The ornamental design for a multifunctional drying rack, as shown and described herein.

DESCRIPTION

FIG. 1 is a front, top perspective view of a multifunctional drying rack showing an embodiment of my design;

FIG. 2 is a top view of the embodiment;

FIG. 3 is a bottom view of the embodiment;

FIG. 4 is a front view of the embodiment;

FIG. 5 is a back view of the embodiment;

FIG. 6 is a right side view of the embodiment; and,

FIG. 7 is a left side view of the embodiment.

All broken lines represent portions of the multifunctional drying rack that form no part of the claimed subject matter. In all embodiments, additional text, logos, graphics, or other surface elements could be present and superimposed on the design shown.
